US00D789934S

(12) **United States Design Patent** (10) **Patent No.:** **US D789,934 S**
(45) **Date of Patent:** **** Jun. 20, 2017**

(54) **KEYBOARD**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/589,773**

(22) Filed: **Jan. 4, 2017**

Related U.S. Application Data

(63) Continuation of application No. 29/538,664, filed on Sep. 4, 2015, now Pat. No. Des. 776,116.

(57) **CLAIM**

The ornamental design for a keyboard, as shown and described.

DESCRIPTION

FIG. 1 is a top front perspective view of a keyboard showing the claimed design;

FIG. 2 is an enlarged view of a key shown in FIG. 1;

FIG. 3 is a front view of the keyboard;

FIG. 4 is a rear view thereof;

FIG. 5 is a left side view thereof;

FIG. 6 is a right side view thereof;

(Continued)

FIG. 7 is a top view thereof; and,
 FIG. 8 is a bottom view thereof.
 The dashed broken lines in the figures show portions of the keyboard that form no part of the claimed design.
 The dot-dash broken lines in the figures show boundaries that form no part of the claimed design.

1 Claim, 5 Drawing Sheets
